(57) **CLAIM**

What is claimed is the ornamental design for a suction station, as shown and described.

DESCRIPTION

FIG. 1 is a perspective view of a suction station showing a new design;

FIG. 2 is a front elevation view thereof;

FIG. 3 is a rear elevation view thereof;

FIG. 4 is a right side elevation view thereof;

FIG. 5 is a left side elevation view;

FIG. 6 is a top plan view thereof; and,

FIG. 7 is a bottom plan view.

The components of the display shown in broken lines illustrate portions of the suction station form no part of the claimed design.
